DISPENSING BOTTLE

Jerome Gould, Encino, Calif., assignor to Abbott Laboratories, North Chicago, Ill., a corporation of Illinois

Filed July 30, 1964, Ser. No. 81,067

Term of patent 14 years

(Cl. D58—8)

Fig 7

I claim:

The ornamental design for a dispensing bottle, substantially as shown.
